UNITED STATES PATENT OFFICE.

WILLIAM HENSMAN, OF SOUTHFIELDS, LONDON, ENGLAND.

FIRE-ESCAPE.

1,273,485.

Specification of Letters Patent. Patented July 23, 1918.

Application filed February 23, 1916. Serial No. 79,986.

To all whom it may concern:

Be it known that I, WILLIAM HENSMAN, a subject of the King of England, residing at 31 Elborough street, Southfields, London, 5 England, have invented certain new and useful Improvements Relating to Fire-Escapes, and I do hereby declare the following to be a full, clear, and exact description of the invention, such as will enable others 10 skilled in the art to which it appertains to make and use the same.

This invention relates to fire escapes and refers to a device of this description which is so constructed, preferably in connection 15 with a table or some similar article of furniture that it is always at hand and available for use, and is adapted when attached to the sill of a window or in some other analogous or suitable position to form a safe 20 means of escape for persons and means for facilitating the salvage of the contents of the building.

In order that my said invention may be clearly understood, I will proceed to describe the same with reference to the drawings accompanying this specification, in 25 which:—

Figures 1 to 4 show diagrammatically the 30 details of construction of the device or apparatus, according to one typical form of construction, illustrating the method of unfolding the device.

Fig. 5 is a perspective view of a table, with my device fitted thereto, the said device being closed.

Fig. 6 is a side elevation of the table, with the escape open, the device itself and its associated parts being identical in all essential details with that illustrated in Fig. 5.

Fig. 7 shows another form of escape, without a table, closed, in side elevation.

Fig. 8 shows the same escape, closed, in front elevation.

Fig. 9 shows the same escape, open, in 45 front elevation.

Fig. 10 shows the same escape, open, in side elevation.

The same symbols of reference are employed to denote similar parts in all the 50 views.

Referring first to Figs. 1 to 4, *a* denotes

the underside of the top of a table, or a plate or sheet of any suitable material to be screwed or otherwise secured thereto.

The plate or sheet *a* is furnished with 55 portions 1, 2 and 3, formed or turned up at right angles to the surface of the said plate or sheet *a*. The portion 1 has hinged to it the sheet *a*¹; the portion 2 has hinged to it the sheet *a*², while the portion 3 has 60 hinged to it the sheet *a*³.

The portion 3 projects by the thickness of a sheet beyond the portion 2 and the portion 2 to a similar extent beyond the 65 portion 1.

In this way, taking the unfolded position, as shown at Fig. 4, in order to fold up the device, the sheet *a*¹ is turned up to come against the table top or sheet *a*, see Fig. 3; the sheet *a*² is then turned in until 70 it rests against the sheet *a*¹, see Fig. 2, after which the sheet *a*³ is turned in until it rests against the sheet *a*², see Fig. 1: thus completing the folding.

Referring now to Figs. 5 and 6 forms of 75 the apparatus are illustrated embodied under the upper part of a table top, the table being of any suitable dimensions, and if desired, constructed of steel tubing or iron rods for the legs and frame, and covered 80 with wood so as to present the ordinary appearance: and the escape apparatus or device comprises a series of sheets, plates or flaps constructed and arranged as already described with reference to Figs. 1 to 4. 85

These sheets plates or flaps are of rigid material, which may be fireproof, or fire-proofed, or covered with fireproof material.

They are hinged together and mounted as previously explained and the largest of 90 the sheets *a* is screwed to or forms parts of the underside of the table top.

When the whole apparatus is folded up it forms a cabinet like device.

The innermost folding sheet *a*¹ is hinged 95 endwise across one end of the back *a*, and this sheet, when open at right angles to the back *a* is adapted to form the bottom or platform of the escape. In the particular form of the device represented, the outer 100 half of this sheet *a*¹ is shaped so as to form a receptacle for a coil of lowering rope,

When lowered the sheet a^1 is supported by hinged side brackets, chains or the like or may rest upon a cross bar b at the lower part of the table legs. The two sheets, a^2 and a^3 , are hinged vertically to the sides of the sheet a and form the sides of the escape when open.

The side sheets, a^2 and a^3 , may as an alternative, be replaced by fireproof canvas sheets, such as those shown at g in the form of the device represented in Figs. 7 to 10.

For suspending the escape the following arrangement is provided:—

Attached near the side edges of the sheet a are rods d , d , which are held in position a short distance, say about 4 inches forward of and 2 inches outside the limits of the sheet a . They are attached at the ends to the legs of the table and supported at a suitable distance along their lengths by an arm c^1 , one such arm being provided for each rod, and placed about two thirds up the length of such rod. e , e are large hooks attached by links y to the rods d , one on each rod, the links being free to slide along the rods d , and the arms c^1 forming stops for the links when the escape is suspended vertically. On each side of the under part of the table top a gate or flap h may be arranged, as shown in Fig. 5, which flap is hinged so that it is forced open by the weight of the hooks when turned out, allowing the hooks to hang freely.

A lowering rope f is roved through an eye attached to a transverse member joining the side rods d , or to an eye suitably attached underneath the top of the table, so that, as a means of escape, a person may either slide down the rope or be lowered by a second person from the platform.

It will be seen that when the device is folded up the whole apparatus resembles a cabinet, the frame and the hooks are contained in a space, a few inches in depth, under the top of the table, and concealed from view under ordinary conditions.

The use of the apparatus will be readily understood.

Upon an alarm of fire, the table is turned upside down, with one end resting on the window sill. It is held horizontally in this position while the hooks e are turned out over the sides of the inverted top. The table is then pushed bodily out through the window, the hooks engaging over the sill, as this operation takes place, and the table becomes suspended, on end, outside the building with the legs pointing outward. The side and bottom sheets of the apparatus open out automatically, thus forming a platform with side screens providing at once a safe refuge in which a limited number of persons may remain until taken off by ladders, fire escapes

or the like, or whence they may slide down the rope to the ground or be lowered in turn by other persons.

The lowering rope f , as the apparatus opens, falls over the edge of the flap a^1 , and therefore hangs vertically from a point well out from the face of the building, so as to keep it, as much as possible, clear of flames, heat and smoke coming from any lower window.

The outer edge of the platform a^1 may be straight as shown at Figs. 1 to 5, or it may be provided at the outer edge at about the part marked w , on Fig. 5 with an inwardly cut loop or curve intended to keep the rope f in the position about the middle of the outer edge of the said flap. Where this arrangement is provided the rope hangs substantially as shown at Fig. 6, and an analogous arrangement is provided in the frame having the same function, in the form of the device illustrated in Figs. 7 to 10, where the loop or recess is seen clearly at Fig. 8 and the rope f is shown as passing down over the same at Fig. 10.

A great amount of salvage of the contents of the building may in many cases be possible, by one person remaining inside the building while safe, and passing out articles to a second person in the refuge, who lowers them to the ground. The person on the inside always has the refuge to resort to for safety when the building becomes untenable.

Referring to the form of the device without the table, and as illustrated at Figs. 7 to 10 in which it is furnished with canvas sides and back sheets: m is a rectangular frame of angle iron on other suitable metal, having arms n at or near the corners for holding the rod frame p which, from the arm q , is brought down to meet the angle iron frame m at the lower end. Across the lower cross end of the rod frame, the bottom sheet a^1 is hinged and on the sides of the frame p , the links carrying the hooks e are attached. At a point about two-thirds up the side rods, the connecting arm q joins either rod to the back, and thus forms a stop for the link of the hook, when the escape becomes vertically suspended.

Above the connecting arms, and on each side rod, an iron swinging bracket r is hinged, to which the upper edges of the canvas sides g are secured.

The platform is supported, when open, by a wire rope or chain s , led around the two upper corner arms, and having both ends fastened to an iron rod h fixed crosswise under the bend of the platform.

The back, sides and bottom are covered with fireproofed canvas sheets g , sewed to each other and the framework is open.

When required for use, the lower end of

the escape is laid on the window sill, the hooks are dropped, and the whole pushed bodily out through the window, with the same result as when the device is used with 5 the table.

It will be understood that I may modify the device, within the scope of my claims, without departing from the principle of my invention.

10 What I claim and desire to secure by Letters Patent of the United States of America is:—

15 1. In a fire escape the combination of a back member, hooks for suspending such member, a substantially rectangular sheet of fireproof material hinged in connection with said backing and adapted in one position to fold against the same, and in another position to turn outward and to form a 20 platform, means for supporting the said platform in the open position when the device is in use, and two fireproof side members hinged to the said backing and adapted when the device is closed to fold over the 25 aforesaid member forming the platform and over one another and when the device is opened to form the sides of a shelter, substantially as described.

20 2. In a fire escape the combination of a backing member, a substantially rectangular framework composed of metal rods connected to said back member, links attached to the sides of the said framework and carrying large hooks, means for stopping the links 35 of the hooks when the escape is suspended vertically, a substantially rectangular sheet of fireproof material hinged in connection with said backing and adapted in one position to fold against the same, and in another position to turn outward and to form a 40 platform, means for supporting the said platform in the open position when the device is in use, and two fireproof side members hinged to the said backing and adapted when 45 the device is closed to fold over the aforesaid member forming the platform and over one another and when the device is opened to form the sides of a shelter, substantially as described.

50 3. In a fire escape, the combination of a table, a back member attached beneath the top of such table, a substantially rectangular

framework composed of metal rods connected to said back member, links attached to the sides of the said framework and carrying large hooks, means for stopping the links of the hooks when the escape is suspended vertically, a substantially rectangular sheet of fireproof material hinged in connection with said backing and adapted in one position to fold against the same, and in another position to turn outward and to form a platform, means for supporting the said platform in the open position when the device is in use, and two fireproof side members 55 hinged to the said backing and adapted when the device is closed to fold over the aforesaid member forming the platform and over one another and when the device is opened to form the sides of a shelter, and 60 means of attachment for a lowering rope, substantially as described.

4. In a fire escape the combination of a table, a back member attached beneath the top of such table, a substantially rectangular 75 framework composed of metal rods connected to the said back member, links attached to the sides of the said framework carrying large hooks, means for stopping the links of the hooks when the escape is suspended vertically, a substantially rectangular sheet of fireproof material hinged in connection with the said backing, and adapted in one position to fold against the same and in another position to turn outward and to form a platform, a recess in the said platform for the reception of a coil of rope for lowering purposes, means for supporting the said platform in the open position when the device is in use, and two fireproof side members 80 hinged in connection with the sides of the backing and adapted when the device is closed to fold over the aforesaid member forming the platform and over one another and when the device is open to form the sides 85 of a shelter, and means for attaching the lowering rope, substantially as described.

In testimony whereof I affix my signature in presence of two witnesses.

WILLIAM HENSMAN.
